UNITED STATES PATENT OFFICE.

CARLOS J. BASSLER, OF PORTLAND, OREGON, ASSIGNOR, BY MESNE ASSIGNMENTS, TO AMERICAN LIQUID METER COMPANY, OF SEATTLE, WASHINGTON, A CORPORATION OF WASHINGTON.

FLUID METER.

Application filed June 21, 1920. Serial No. 390,605.

To all whom it may concern:

Be it known that I, CARLOS J. BASSLER, a citizen of the United States of America, and resident of the city of Portland, in the 5 county of Multnomah and State of Oregon, have invented certain new and useful Improvements in Fluid Meters, of which the following is a specification.

My invention comprises an improvement 10 in fluid meters. My present invention is particularly intended as an improvement upon the meter shown in my copending application, Serial No. 362,423, and is capable of all the uses and variations described in 15 connection with this meter.

The principal object of my invention is to provide means for automatically compensating for expansion of the fluid being measured, due to heat. The device may 20 be set to compensate for contraction, as well, but it would generally, in use, be set at a sufficiently low initial temperature, that any variation in volume would only be due to expansion.

Another object of my invention is to provide, in addition to the automatic compensating means, independent means for regulating the device to compensate for expansion, to the end that the initial temperature 30 for which the automatic compensating device is set may be any desired temperature, within reasonable limits.

A further object of my invention is to provide a more perfect meter of the type shown in my application referred to above.

My present invention comprises those novel parts and combinations thereof which are shown in the accompanying drawings, described in the specification, and particularly pointed out in the claims terminating the same.

In the accompanying drawings I have shown my invention in a form which is now preferred by me.

Figure 1 is an axial section through the meter.

Figure 2 is an axial section through an end of the meter, taken at right angles to Figure 1.

While the circumferential expansion of

the material of the cylinder itself is negligible in comparison with the cubical expansion of the body of liquid being measured yet even this circumferential expansion may be compensated for, if desired, by using a 55 liquid in cylinder 57 having a slightly lower coefficient of expansion than the liquid being measured. However this will ordinarily not be found necessary because the difference in result arising from the expansion of the 60 meter body is so slight as to be immaterial.

As in general my present device resembles that shown in my application referred to above, it will not be necessary, to explain its construction in detail. A piston 4 is reciprocable within a cylinder 1. This cylinder is closed by the heads 10; in each of which are mounted the seats 12 and 13 for the tubular, axially-reciprocable inlet valves 2 and outlet valves 3, respectively. Inlet passages 14 and 65 outlet passages 15 in the cylinder and heads, communicate respectively with ports 16 and 17 in the respective seats 12 and 13. The tubular valves 2 and 3 are open at both ends, and are provided with ports 21 and 31, respectively, in their sides, which are adapted 70 to communicate at the proper time with the port 16 or 17, as the case may be.

The pairs of valves 2 and 3 at each end of the cylinder are connected by means of a 75 yoke 8. A spindle 22 or 32 upon the inner ends of the valves is held in the end of the yoke 8 to turn freely therein about its axis. The spindle is preferably a loose fit in the yoke, as shown in an exaggerated manner in 80 Figure 2, and this permits a slight rocking transversely of its axis. These two possible movements, free rotation upon its axis and a slight transverse pivoting or rocking, permit 85 the valve to give while moving, to overcome 90 any tendency to cock or stick. This is necessary because the valves must be a tight fit in their seats, and they must move quickly. Such a construction also permits expansion 95 of the yoke 8 without producing a tendency for the valves to cock. The yokes 8 at opposite ends of the cylinder are rigidly connected by a rod 80, extending through the hub 40 of the piston.

I prefer that in the ends of the cylinder, 100

in position to receive the outer ends of the tubular valves 2 or 3, there be formed annular grooves 18, of slightly greater width than the thickness of the valve walls. These 5 grooves form dashpots for the valves, and eliminate pounding and wear thereupon. It is very desirable that stops be provided to accurately limit the movement of the valves, and to cause their ports to register exactly, 10 but it is equally desirable that pounding should be eliminated.

I employ a suitable power storage mechanism to actuate the valves, this being energized by the piston in its travel, and tripped 15 when the piston has reached the predetermined limit of its travel in each direction, to thereby reverse the position of the valves and the motion of the piston. The form of power storage mechanism shown herein consists of the springs 41 surrounding the rod 80 at each side of the piston 4, which springs rest at one end in the cups 42, secured upon the rod 80 or abutting against the yokes 8. The outside of the cups 42 20 forms a shoulder 43, against which a cooperating shoulder 50 carried by a dog 5 normally lies to prevent outward movement of the spring 41 and cup 42 under pressure. Beveled surfaces 44 are provided near the 25 hub of the piston 4, which engage the trips 53 or 55, which will be hereinafter described, to release the power storage mechanism and to reverse the valves.

At one end of the cylinder 1 the detent or 30 dog 5 is in all respects similar to that shown in my application referred to above. It comprises a rod 51, threaded at one end in the shouldered dog 5, and provided at its outer end with a hardened ball 53. The 35 dog 5 is pivoted at 52 in the cylinder head 10, and the cylinder head is bored at 19 and plugged, to permit adjustment of the rod 51 in the dog 5.

The detent at the opposite end of the piston is similar in many respects to the one described. The rod 51, is however, freely 40 slidable in the dog 5, and its outer end 55 is provided with a curved surface to contact with the beveled surface 44 upon the piston, and is extended upward to support 45 one end of a spring 56. Upon the dog 5, with its axis parallel to the axis of the rod 51, is a small cylinder 57, which is filled 50 with a suitable fluid. This small cylinder 57 is closed at both ends, at one end by a plug 58 which supports the other end of the spring 56, and at its other end by a plunger 59 extending thereinto, and connected outside of the cylinder to one end of 55 the rod 51. The spring 56 urges the plunger 59 into the cylinder 57, and should be sufficiently strong to resist the thrust of the piston 4 in tripping. Thus it will be seen 60 that the yokes 8 and the springs 41 constitute actuating means for the valves and

that there is provided a thermostatically controlled restraining means or detent for one of said actuating means which restraining means or detent, as a whole, comprises the dog 5, cylinder 57, rod 51, spring 56 70 and plunger 59, the effective length of this detent as a whole being varied thermostatically.

The fluid which fills the cylinder 57 should have a coefficient of expansion equal 75 to that of the fluid being measured in the cylinder 1, and its volume should bear the same relation to the area of the plunger 59 that the volume of the fluid being measured in the cylinder 1 bears to the area of 80 the piston 4. In this manner a given change of temperature of the fluid being measured will effect a given expansion of its volume, requiring a given lineal expansion of the travel of the piston 4, while the same change in temperature will effect a proportional expansion of the volume in the small cylinder 57, causing a proportional displacement of the plunger 59. This will cause a recession of the end 55 of the detent at this end an amount equal to the required increase in the travel of the piston, thus automatically compensating for the expansion due to increased temperature.

The same result might be secured by careful calculations of volumes, distances, angles, and coefficients of expansion, if a fluid were used in the cylinder 57 which had a different coefficient of expansion than the fluid being measured, but I prefer to obviate such difficulties and the possibility of errors due to the careful calculations involved, by using a fluid having the same coefficient, and by making the volumes and piston areas proportional, as explained above.

It is important that the cylinder 57 be tightly closed and entirely filled with the suitable fluid, and that no air or foreign fluid be permitted to remain therein, as this would cause improper expansion in the cylinder. To fill the cylinder completely any suitable method may be employed, as by screwing in the cap 58 and permitting the fluid to overflow from a small opening therein, and then closing this small opening. The cylinder should be filled with the fluid at as low a temperature as it would be desired to use the meter, and the plunger 59 at this temperature should be very slightly projected from its innermost position, to make certain that the cylinder is full.

With the meter as described it is possible to adjust the length of stroke of the piston exactly for any given temperature by adjusting the rod 51 which is threaded in the dog 5, through the opening 19. After this initial adjustment, any adjustment of the piston stroke to compensate for temperature changes is automatically cared for by the detent at the opposite end of the cylinder.

der. Adjustments for wear, which would rarely be required, may be effected through the opening 19.

What I claim as my invention is:

5. 1. In a fluid meter, a cylinder, a piston mounted therein, inlet and outlet valves controlling the supply to and discharge from said cylinder, power storage mechanism for operating said valves energized by the piston in its travel, and a detent for said power storage mechanism comprising a dog having a shoulder adapted to be engaged by said power storage mechanism and fixedly pivoted within the cylinder, a trip connected with 15 said dog and adapted to be engaged by the piston to trip the power storage mechanism, and thermostatically-controlled means for varying the relative positions of the shoulder and the trip.
20. 2. A device as in claim 1, said thermostatically-controlled means comprising a cylinder filled with a fluid and fixed to one of said relatively-movable members, and a plunger movable therein and fixed to the 25 other member.
30. 3. A device as in claim 1, said thermostatically-controlled means comprising a small cylinder filled with a fluid having a coefficient of expansion equal to that of the fluid being measured, said cylinder being fixed to one of said relatively-movable members, and a plunger therein and fixed to the other member, the ratio of the volume of 35 said small cylinder to the area of the plunger being equal to the ratio of the volume to be measured in the large cylinder to the area of the piston.
40. 4. A device as in claim 1, said thermostatically-controlled means comprising a cylinder mounted upon said dog and filled with an expandible fluid, a plunger movable therein and secured to said trip to cause axial reciprocation thereof, and a spring acting on 45 said trip in opposition to said plunger.
5. 5. In a fluid meter, a cylinder, a piston mounted therein, inlet and outlet valves controlling the supply to and discharge from said cylinder, means controlled by the movement of the piston for actuating said valves and thermostatically-controlled means which 50 control said valve actuating means to lengthen the piston stroke to compensate for expansion of the fluid.
55. 6. In a fluid meter, a cylinder, a piston mounted therein, inlet and outlet valves controlling the supply to and discharge from said cylinder, actuating means for the valves, a controlling element for the said actuating means including a shiftable thermostatic element the position of which is shifted by variations of temperature of the fluid 60 being measured and the position of which determines the time in the piston's stroke at which said controlling means will act to thereby automatically compensate for ex-

pansion of the fluid due to heat, and manually settable means for independently varying the piston stroke.

7. In a fluid meter, a cylinder, a piston mounted therein, inlet and outlet valves controlling the supply to and discharge from said cylinder, an actuating means for said valves, a detent for said actuating means comprising an element disposed in the path of movement of the piston and actuated thereby at the end of the piston travel to permit movement of the valves under the influence of their actuating means and thermostatically controlled means for varying the position of said element longitudinally 75 of the cylinder to thereby vary the point in the piston travel at which said piston will actuate said element.

8. In a fluid meter, a cylinder, a piston mounted therein, inlet and outlet valves controlling the supply to and discharge from said cylinder, an actuating means for said valves and a restraining element for said actuating means comprising a thermostatically controlled part actuated by the piston 80 at the end of the piston's travel to move the restraining element from restraining position with respect to the said actuating means, the position of the thermostatically controlled part being shifted by changes of 85 temperature of the fluid being measured to vary the point in the piston's stroke at which the piston will actuate said part.

9. A fluid meter comprising a measuring cylinder, a piston movable in said cylinder, means for controlling the stroke of the piston to thereby determine the meter discharge, said controlling means including an adjustable element and a thermostatically operated means for adjusting said element. 100

10. A fluid meter having a cylinder and a movable piston forming the measuring mechanism, a piston controlling mechanism comprising a part actuated by the piston at an end of its stroke to actuate said controlling mechanism, and thermostatically adjustable means acting upon said part to vary the time of its actuation by the piston. 105

11. A fluid meter having a cylinder and a fluid-actuated piston movable therein forming the measuring mechanism, a piston-movement limiting means comprising a part actuated by the piston at an end of its stroke to limit the movement of the piston, and thermostatically-controlled means for automatically adjusting the position of said part to vary the piston travel in conformity with the temperature of the fluid. 115

12. A fluid-meter having a cylinder and a piston reciprocable therein forming the measuring mechanism, two piston-movement limiting means each including a part actuated by the piston at its respective end of the piston stroke to limit the movement of the piston, means for manually adjusting 120

the position of one of said parts to vary its point of limitation of the piston movement, and thermostatically controlled means for automatically adjusting the position of 5 the other part to vary its point of limitation of the piston travel in conformity with the temperature of the fluid.

13. In combination a meter comprising a measuring chamber, means for admitting 10 fluid thereto and discharging fluid therefrom and thermostatically operable means for varying the effective size of the measuring chamber to increase the same as the temperature of the fluid being measured rises 15 and decrease the same as the temperature of said fluid decreases.

14. In combination a fluid measuring meter comprising a measuring chamber, an element movable therein under the influence 20 of the fluid being measured and thermostatically controlled means for varying the movement of said element in the chamber in accordance with variations in the tempera-

ture of the fluid being measured to increase the effective measuring capacity of said chamber as the said temperature rises and decrease its capacity as said temperature lowers.

15. In a fluid meter a cylinder, a piston mounted therein, inlet and outlet valves controlling the supply to and discharge from said cylinder, an actuating means for said valves and a thermostatic restraining means for said actuating means comprising a cylinder filled with an expansible fluid and a 35 plunger movable in said cylinder, the position of said plunger being shifted by variations in temperature of the fluid being measured to correspondingly vary the time at which said restraining means will be actuated to permit the actuating means to move said valves.

Signed at Seattle, King County, Washington this 12th day of June, 1920.

CARLOS J. BASSLER.
